UNITED STATES PATENT OFFICE

ROBERT D'ORLEANS, OF SAN FRANCISCO, CALIFORNIA

HAIR WAVING DEVICE

Application filed April 10, 1929. Serial No. 354,025.

This invention relates to improvements in hair waving devices and has particular reference to a clamp for holding and forming what is commonly called a permanent wave.

Another object of this invention is to produce a device of this character which may be employed with the customary heating means.

A further object is to produce a device of this character which is insulated from the head and one which will not cause any burning or discomfort to the person.

A further object is to provide means whereby a perfect seal is formed between the clamp and the hair, thus eliminating the danger of steam passing through to the scalp.

A further object is to provide a device of this character which is simple, and therefore economical to manufacture.

Other objects and advantages will be apparent during the course of the following description.

In the accompanying drawings forming a part of this specification, and in which like numerals are employed to designate like parts throughout the same,

Figure I is a side elevation of my device,

Figure II is an end elevation looking in the direction of the arrow B,

Figure III is an end elevation looking in the direction of the arrow A,

Figure IV is a top plan view of the clamping elements with the twisting roll removed,

Figure V is a side elevation of the rubber packing,

Figure VI is a cross-sectional view of the rubber packing on a slightly large scale, and

Figure VII is a vertical cross-sectional view through the entire device as shown in Figure I.

At the present time various forms of clamps are used in order to hold the hair while the permanent wave is being formed therein. These clamps permit a large amount of heat to be radiated to the scalp,

or permit the steam generated by the chemi-

cal to escape from the device and injure the scalp. Either of these may result in serious burns which makes permanent waving objectionable.

I have therefore provided a clamp where-in the device is insulated from the head and provision is made for sealing the hair so that the steam cannot escape to the scalp.

At the same time, I have provided a clamp which is adjustable and which operates on either fine or coarse hair.

In the accompanying drawings wherein for the purpose of illustration is shown a preferred embodiment of my invention, the numerals 5 and 6 designate parallel clamping members which are each recessed as shown in Figures 4 and 7 and perforations are caused to pass therethrough which are shown at 7. These perforations, together with an undercut 8 provide for the ventilation as will be hereinafter described. The clamping members 5 and 6 are connected to the slide 9, the clamping member being hinged as at 11 while the clamping member 6 is slidably held in the slide 9 through the medium of a screw 10.

To the opposite end of the member 5 is pivoted as at 13, a hinged latch 14 having a threaded portion 16 upon which a nut 17 is positioned. This construction permits the two members 5 and 6 to be adjusted parallel to each other so that the rubber seal 18 may be effectively clamped there-between. The shape of the rubber seal is best shown in Figs. V, VI and VII.

A bracket 19 is carried upon the slide 9 and serves to rotatably position thru the medium of a blot 21, a hair curling roller 22 which is preferably tapered as best shown in Fig. 1. A boss 25 formed upon the opposite end of the roller is adapted to have a key positioned thereon, for the purpose of rotating the roller.

Secured to the under side of the clamping members 5 and 6, are insulating plates 23

and 24. One of these plates is preferably made of cork or some similar heat resisting substance.

The result of this construction is that when it is desired to place a permanent wave in the hair, a strand of hair is first passed thru the rubber member 18 and the tip is moved into close proximity with the scalp. The two clamping members 5 and 6 are now brought around the rubber and locked to each other, after which the screw 10 and the nut 17 are tightened so as to squeeze the rubber 18 and thereby perfect a tight seal between the rubber and the hair, and thus prevent steam from the hair reaching the scalp and burning the same. A roller is now positioned in the bracket 19 and the end of the hair is loosely wound thereon. By now using a key upon the boss 23 the roller is rotated until the hair is tightly wound upon the roller in the manner shown in Figure VII. In some instances, the hair is first wet and the end of the hair is then wound upon the end of the roller for a short distance, and then the roller is engaged in winding position, after which the key is used and the roller rotated until the balance of the hair has been wound tightly upon the roller.

This tightening of the roller, while stretching the hair, will not transmit a pull through to the scalp as is common with many forms of permanent wavers, consequently, the pull upon the hair roots will not cause the suffering now experienced.

35 The hair is now damped with the proper chemicals, a small pad is placed over the roller with the hair thereon and the heating clamp shown in dotted lines in Figures I and VII is applied.

40 When the steam which is generated by the heat starts to escape, the same may pass away into the atmosphere and due to the construction of the clamping members 5 and 6, it will be apparent that air may pass through the under cut 8, thence through the perforations 7, which circulation will prevent any heat from being transmitted to the scalp.

45 It is to be understood that the form of my invention herewith shown and described is to be taken as a preferred example of the same and that various changes relative to the shape, size, material and arrangement of parts may be resorted to without departing from the spirit of the invention or the scope of the subjoined claim.

Having thus described my invention, I claim:—

50 In a device of the character described, a pair of clamping members pivotally and slidably connected one to the other, a T-shaped removably resilient seal adapted to be positioned between said clamping member, a slot formed thru said seal at right angles to said clamping members, means for compressing

55 said T-shaped seal between said clamping members, a bracket carried on said clamping members, a roller rotatably carried in said bracket, insulating members carried on said clamping members and having a greater portion of their length spaced from said clamping members, whereby air circulation may take place between said clamping members and said insulating members, for the purpose specified.

60 In testimony whereof I affix my signature,
ROBERT D'ORLEANS.
